CUP DISPENSER

Harry Sebell, Boston, Mass., assignor to Boston Envelope Company, Dedham, Mass., a corporation of Massachusetts

Application March 16, 1935, Serial No. 11,450

3 Claims. (Cl. 312—55)

This invention relates to cup dispensers designed to dispense or deliver individual cups from a stack of cups, and it has for its general object to provide an improved cup dispenser which is certain and effective in operation and which is of sturdy construction.

Other objects of the invention are to provide various improvements in cup dispensers which will be more fully hereinafter set forth.

10 In the drawings wherein I have illustrated a selected embodiment of my invention,

Fig. 1 is a partial sectional view of a cup dispenser showing my improvements.

Fig. 2 is a view similar to Fig. 1 but showing a 15 cup being ejected from the container.

Fig. 3 is a view similar to Figs. 1 and 2 showing the cup ejector in the position it assumes during its retracting movement.

Fig. 4 is a section on the line 4—4 Fig. 1.

Fig. 5 is a section on the line 5—5 Fig. 1.

Fig. 6 is a section on the line 6—6 Fig. 4.

Fig. 7 is a section on the line 7—7 Fig. 4.

Fig. 8 is a fragmentary sectional view showing the cup ejector in its operative position.

25 Fig. 9 is a perspective view showing a type of cup which is well adapted for use with my cup dispenser.

While my improved cup dispenser may be used for dispensing cups of different construction, yet it is especially useful in dispensing a cup such as shown in Fig. 9. This cup, which is indicated at 1, is a folded paper cup that is folded from a blank in such a way as to present the side seam 2 and the bottom flap or fold 3 which closes 30 the bottom of the cup, and which is folded over against the side of the cup and adhesively united thereto. This bottom flap 3 presents a shoulder 4 with which the cup ejector of my improved cup dispenser co-operates to deliver the cups singly.

40 The cup dispenser herein shown comprises a casing or container 5 adapted to hold a stack 6 of folded cups 1 such as shown in Fig. 9, said container having the inclined bottom 7 on which the cups rest and being provided on its front side 45 with a cup dispensing slit 8 through which the bottom cup of the stack is ejected as usual in cup dispensers of this type. The cups are arranged in the stack so that the flap 3 of each cup is on the under side thereof and adjacent the 50 front of the container 5.

The bottom cup 1 of the stack is ejected through the delivery slit 8 by means of a cup ejector 9 which is situated below the container bottom 7 and is provided at its forward end with a raised 55 cup-engaging portion 10 that operates through a

slot 11 with which the bottom 7 of the container is provided.

The cup ejector 9 is movable toward and from the cup delivery slit 8 and is mounted so that the cup-engaging portion 10 thereof may be raised and lowered. In the normal retracted position of the cup ejector 9 the cup-engaging portion thereof occupies the rear portion of the slot 11 and is situated substantially flush with the bottom 7 as shown in Fig. 1.

Means are provided for giving the cup ejector a forward cup-ejecting movement during which it is raised into the dotted line position Fig. 1 and into the full line position Fig. 8, and thereby pressed firmly against the bottom cup 1 of the stack. As the cup ejector moves forwardly the edge 12 thereof engages the shoulder 4 of the bottom cup and carries said cup forwardly and partially through the delivery slit 8 as shown in Fig. 2. The partially delivered cup can then be grasped by the operator and withdrawn from the casing and the cup ejector is then returned to its normal position. As it begins its return movement it is lowered into a position flush with the bottom 7 of the container, which position it retains during the entire retracting movement.

The cup ejector is given its forward cup-ejecting movement and its return movement through the medium of a slide 13 which is situated beneath the bottom 7 and is guided in suitable ways 14 formed in the guiding members 15, 16 that are secured underneath and to the bottom 7 of the container. This slide has a pull member 17 secured thereto by which it may be drawn forwardly and it is acted upon by suitable return springs 18, 19 which return it to its rearward position. The pull member 17 is formed with the head portion 20 and with the rearward extension 21. The slide 13 is provided on one side at its forward end with a depending boss 22 to which the head portion 20 of the pull member 17 is secured through the medium of a screw 23 (see Fig. 6). Said slide is also provided at its rear end on the opposite side with a depending rib 24 having a horizontal flange 25 to which the rear end of the rear extension 21 of the pull member is secured by suitable screws 26. The return springs 18, 19 are secured at their forward ends to the opposite sides of the head portion 20 and at their rear ends said springs are secured to the guiding members 15, 16 as shown at 27.

The cup ejector 9 is shown as pivotally mounted on the slide 13, and for this purpose the slide is provided with two depending bosses 28 and 55

the cup ejector is provided with a boss 29 which is received between the bosses 28 and is pivotally secured thereto through the medium of a pivot pin 30 extending through the alined bosses 28, 29. The cup ejector is provided with a tail portion 31 extending some distance to the rear of its pivotal mounting, and means are provided which co-operate with this tail portion to cause the necessary vertical movement of the cup-engaging portion 10 of the cup ejector. For this purpose I have provided herein a switch cam construction arranged so that as the cup ejector begins its forward cup-ejecting movement the tail portion 31 of the cup ejector will be depressed, thereby raising the cup ejector portion into the dotted line position Fig. 1 so that as the cup ejector continues its forward movement the edge 12 thereof will engage the shoulder 4 of the bottom cup and move it forwardly partially through the cup delivery slit 8, said switch cam being further so constructed that as the cup ejector begins its return or backward movement the tail portion 31 will be elevated thereby lowering the cup-ejecting portion into a position flush with the bottom 7 of the container. The switch cam which accomplishes this is indicated at 32 and it operates in an opening 33 formed in a flange portion 34 which is integral with and depends from the guiding member 16. This switch cam 32 is shown as being integral with a plate 35 which is situated at the side of the flange 34 and is pivoted thereto at 36. The plate 35 is acted upon by a spring 37 which is anchored at one end to the pivotal bolt 36 and at its other end acts against a pin 38 carried by the plate 35. This spring normally tends to hold the plate in raised position shown in Figs. 1 and 2 but permits a downward swinging movement of the plate. The periphery of the switch cam 32 forms with the walls of the opening 33 a cam track in which operates a stud 39 extending laterally from the tail end 31 of the cup ejector.

When the cup ejector is in its rearmost position shown in Fig. 1 the follower 39 will be at the upper rear corner of the opening 33 in the rear of the switch cam 32 which is then in its raised position shown in Figs. 1 and 2. As the pull member is drawn forwardly the follower 39 engages the inclined face 40 of the switch cam 32 and moves from the full line position shown in Fig. 1 to the dotted line position Figs. 1 and 2. During this movement the tail end 31 of the cup ejector is moved downwardly and the cup-engaging portion is moved upwardly against the stack of cups as shown in dotted lines Fig. 1 and full lines Fig. 8. This upward movement of the cup-engaging portion 10 causes it to press against cups and lift the bottom cup slightly. As the pull member and slide continue their forward movement the follower 39 travels in the cam track formed by the under face 41 of the switch cam and the lower edge 42 of the opening 33. The tail portion of the cup ejector is thus held in its lowered position as it moves forwardly and the cup-engaging portion 10 is thus maintained in its elevated position. During the forward movement of the cup ejector the edge 12 will engage the shoulder 4 of the bottom cup 1 of the stack and will carry said cup forwardly, thereby partially ejecting it through the slit 8 as shown in Fig. 2. When the slide has been moved forward sufficiently to cause the follower 39 to pass out from under the switch cam 32 as shown in full lines Fig. 2, then the tail portion of the cup ejector will be automatically raised by the action

of a spring to carry the follower 39 into the dotted line position Fig. 2, thereby lowering the cup-engaging portion 10 into a position flush with the bottom 7 of the container and as the slide has its retracting movement the follower 39 will move backwardly above the switch cam 32, the latter swinging downwardly about its pivot 36 to permit the follower to pass. For thus raising the tail portion of the cup ejector I have provided a spring 43 which encircles a pin 44 that is rigid with the slide 13 and extends through an opening 45 in the tail portion 31 of the cup ejector. The spring 43 is confined between a washer 46 that engages the tail portion 31 and a head or nut 47 with which the stud 44 is provided. This spring thus normally tends to hold the cup ejector in the position shown in Figs. 1 and 3.

As the cup ejector starts its forward movement and the tail portion 31 is swung downwardly by engagement of the follower 39 with the cam face 40, the spring 43 will be compressed. As soon as the cup ejector reaches the position shown in Fig. 2 in which the follower 39 has been moved out from under the switch cam then the spring 43 raises the tail portion 31 of the cup ejector and carries the follower 39 into a position so that on a return movement it will pass over the upper face of a switch cam 32. When the slide and cup ejector have been moved back into their rearmost position and the follower 39 will have passed off of the switch cam which is then held in its raised position by the spring arm 37 so that on the next forward movement of the cup ejector the follower will engage the face 40 of the switch cam 32 and be carried underneath the latter.

I claim.

1. A cup dispenser comprising a container for holding a stack of cups, said container having an opening in its bottom and a discharge slit between its bottom and its front wall, a slide beneath the bottom, means supporting the slide for forward and backward reciprocating movement, a cup ejector pivoted intermediate of its ends to the slide and having at its front end a cup-engaging portion for engaging the lowermost cup of said stack through said opening thereby to eject the cup through said discharge slit, means for moving the slide backwardly and forwardly, a switch cam supported in depending relation from the bottom and adapted to cooperate with the rear end of the cup ejector to hold the cup-engaging portion thereof raised through said opening when the slide is moved forwardly, and to hold said cup-engaging portion in a lowered position when the slide is moved rearwardly and spring means supported by said slide for raising the rear end of the cup ejector when it reaches the forward end of the stroke thereby to shift the cup-engaging portion to lowered position. 60

2. A cup dispenser comprising a container for holding a stack of cups, said container having an opening in its bottom and a discharge slit, a manually-operable reciprocating slide beneath the container, a slide-supporting guide situated beneath the container and supported thereby, a cup ejector pivoted intermediate of its ends to the slide and having a cup-engaging portion at its front end, said guide being provided with a depending flange having an opening therein, a pivoted switch cam received within said opening, a follower on the end of the cup ejector cooperating with said cam and the wall of said opening to swing the cup ejector in a direction to raise the cup-engaging portion through an opening in 70 75

the bottom of the container and in the position to engage the bottom cup of the stack during the initial forward movement of the slide and to hold the cup ejector in such position until the slide completes its forward movement, and a spring acting on the cup ejector and operating at the end of the forward movement of the slide to turn the cup ejector about its pivot thereby to lower the cup-engaging portion thereof into said opening, said switch cam operating to hold the cup-engaging portion in such lowered position during the return movement of the slide.

3. A cup dispenser comprising a container for holding a stack of cups, said container having an opening in its bottom and a discharge slit, a manually-operable reciprocating slide beneath the bottom of the container, a slide-supporting guide situated beneath the container and sup-

ported thereby, a cup ejector pivoted intermediate of its ends to the slide and having a cup-engaging portion at its front end, a switch cam cooperating with the rear end of the cup ejector to turn the latter about its pivot and raise the cup-engaging portion through said opening into engagement with the bottom cup of the stack as the slide starts its forward movement and to maintain said cup-engaging portion in its raised position during the forward movement, and a spring carried by the slide and acting against the rear end of the cup ejector to return the cup ejector to normal position with the cup-engaging portion lowered into said opening when the slide completes its forward movement, said switch cam holding the cup-engaging portion in its lowered position during the entire return movement.

HARRY SEBELL.
